Inventor:
L. H. Thomas
Geo. John C. Pasterkatz

UNITED STATES PATENT OFFICE.

LEVI H. THOMAS, OF CHICAGO, ILLINOIS.

INK-BOTTLE.

SPECIFICATION forming part of Letters Patent No. 331,843, dated December 8, 1885.

Application filed January 12, 1885. Serial No. 152,598. (No model.)

To all whom it may concern:

Be it known that I, LEVI H. THOMAS, a citizen of the United States, residing at Chicago, in the county of Cook and State of Illinois, have invented certain new and useful 5 Improvements in Ink-Bottles; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

Writing-ink has hitherto been put up in 15 bottles of glass and earthenware, which materials possess the advantage of not damaging the ink by corrosion of the containing vessel. Bottles of glass and earthenware are, however, 20 frequently broken in handling and transportation, with great risk to adjacent goods. Such bottles, when exposed to excessive cold, are also subject to breakage by reason of the freezing of their contents. Ordinary metal 25 cans, while more durable than vessels of glass or earthenware, are unsuitable for containing ink on account of the corroding effect of the ink on the metal, and the consequent deterioration in the quality of the ink. These difficulties have been obviated at considerable 30 expense by the employment of an ink-bottle having a metallic body provided with an interior coating of pitch, as described in Patent No. 286,893, to William A. Auble, dated October 16, 1883, and assigned to me. That 35 bottle, being formed of metal and wood, is more durable than a bottle of glass or earthenware, while its interior coating of pitch preserves it from corrosion and prevents molding of the 40 ink, as well as other injury.

The object of the invention here presented is to reduce the expense of manufacture and provide for certain improvements in the ink bottle or can described in the above-named 45 patent; and to this end my invention consists of an ink-bottle or can having a paper or cardboard body, with rigid bottom and top, a metallic neck and spout, and an interior coating of water-proof material, as hereinafter 50 more fully set forth.

The invention is illustrated in the annexed

drawing, which represents a vertical section of my improved ink bottle or can.

The body A of the ink-bottle is preferably formed as a cylinder by winding successive 55 layers or sheets of paper on a mandrel and uniting them by a suitable cement. Into each end of the tubular body so formed is secured a disk, as B C, of wood or other rigid material, said disks being formed with shoulders 60 a a, that afford a bearing for the ends of the tubular body. The lower disk or bottom, B, affords a firm base for the bottle, while the upper disk or top, C, is centrally perforated 65 for the attachment of a metallic neck, D, which terminates in a pouring-spout, E, and is fitted with a stopper, F, of any desired material.

In order to render the paper body A impervious to moisture, so as to prevent it from 70 absorbing the contents of the bottle, as well as to impart a preservative quality to the ink and prevent corrosion of the metallic neck D, an interior coating, b, of pitch or other water-proof and preservative preparation, is 75 applied to the bottle, as shown in the drawing. The waterproofing-liquid may be best applied by filling the ink-bottle with such compound before the top C is adjusted, then secure the top in place and pour the water-proof compound out through the neck of the bottle, thus obtaining a complete and uniform coating of the interior of the paper bottle and its neck, whereby absorption and corrosion are effectively prevented when the bottle is subsequently 80 filled with ink.

The stopper F may be made of wood and coated with pitch, paraffine, or like material, or an ordinary cork or other stopper may be 85 employed.

The advantages of an ink bottle or can constructed as described, and having an elastic water-proofed paper body, will be apparent in its diminished cost and weight as compared 95 with vessels heretofore in use for like purposes. This construction also obviates the liability of breakage from freezing of its contents when exposed to low temperatures, and further decreases the risks of transportation, and renders it possible to procure low rates of 100 freight. These features are important to the trade, in which large quantities of ink in pack-

ages of various sizes have frequently to be shipped in cold weather.

Having thus described my invention, what I claim as new, and desire to secure by Letters

5 Patent, is—

1. An ink-bottle consisting of a paper body, a bottom, a wooden top, and a metallic neck, the interior of said bottle being provided with a water-proof coating, substantially as described.

2. An ink-bottle consisting of the paper body A, having a bottom, B, and top C of

rigid material, a metallic neck, D, provided with spout E, a stopper, F, and an interior water-proof coating, b, substantially as described.

In testimony whereof I affix my signature in presence of two witnesses.

LEVI H. THOMAS.

Witnesses:

LOUIS BECKHARDT,
WM. P. WILLIAMS.
